[57] CLAIM

The ornamental design for a mobile radio with handle, as shown and described.

DESCRIPTION

FIG. 1 is a top plan view of a mobile radio with handle according to my design with the handle in an extended position;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom plan view thereof;

FIG. 7 is a view similar to FIG. 1 illustrating a further form of mobile radio with handle;

FIG. 8 is a front elevational view thereof;

FIG. 9 is a left side elevational view thereof;

FIG. 10 is a right side elevational view thereof;

FIG. 11 is a rear elevational view thereof;

FIG. 12 is a bottom plan view thereof;

FIG. 13 is a view similar to FIG. 3 illustrating the handle of the mobile radio in a latched position, the dashed lines illustrating the environment of a bracket for holding the mobile radio hereof and forming no part of the present design;

FIG. 14 is a front elevational view of the mobile radio illustrated in FIGS. 1-6 with the handle in a latched position; and,

FIG. 15 is a front elevational view of the embodiment hereof illustrated in FIGS. 7-12, with the handle in a latched position.

FIG. 1**FIG. 2**FIG. 3

FIG. 4

FIG. 5**FIG. 6**

FIG. 7**FIG. 8**FIG. 9

FIG. 10

FIG. 11**FIG. 12**

FIG. 13**FIG. 14****FIG. 15**
